(57) CLAIM

The ornamental design for a panel for the back of a seat, as shown and described.

DESCRIPTION

FIG. 1 is a left hand side view of a panel according to the invention, the right hand side being its mirror image;

FIG. 2 is an elevation view of the front of the panel of FIG. 1;

FIG. 3 is a top view of FIG. 2;

FIG. 4 is an elevation view of the back side of the panel of FIG. 2; and,

FIG. 5 is a bottom view of FIG. 2.

The broken lines shown in FIG. 2 are for illustrative purposes only and form no part of the claimed design.
